UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,246,755.

Specification of Letters Patent. Patented Nov. 13, 1917.

Application filed May 22, 1916. Serial No. 99,058.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States No. 436,532 to O. Mergenthaler, wherein circulating mat-

15 rices are released from a magazine in the order in which their characters are to appear in print and then assembled in line, the composed line transferred to the face of a mold, the mold filled with molten metal to 20 form a slug or linotype against the matrices which produce the type characters thereon, and the matrices thereafter elevated and returned through distributing mechanism to the magazine from which they started.

25 More particularly, it has reference to machines wherein the magazine is removable to permit the substitution of another containing matrices of a different face or font. In some machines, and particularly when 30

the escapements are carried by the magazine, it is necessary to disconnect the escapements and their actuating devices before the magazine can be removed, but before this is done, the escapements should be 35 locked against action, as otherwise the disconnection would result in the release of the lowermost matrices from the magazine, causing considerable annoyance and inconvenience or even injury to the parts.

40 One of the objects of my present invention is to avoid this liability, and to that end, specifically I provide means to prevent the disconnection of the actuating devices from the escapements until the latter have 45 first been locked against action. Other objects and the means employed for carrying them into effect will be specifically pointed out in the detailed description to follow.

In the accompanying drawings, I have 50 shown my invention in preferred form and by way of example and as applied to a specific style of machine, but obviously many changes and variations may be made therein and in its mode of application with-

out departure from its spirit. Generally 55 speaking, I desire it to be understood that I do not limit myself to any specific form or embodiment, except in so far as such limitations are specified in the claims.

Referring to the drawings:

Figure 1 is a side elevation of a portion of a linotype machine, certain parts being broken away, with my invention applied thereto;

Fig. 1^a is a detail-view;

Fig. 2 is a view similar to Fig. 1 with some of the parts in different position;

Fig. 2^a is a detail-view;

Fig. 3 illustrates a form similar to that of Figs. 1 and 2, showing the magazine 70 in full and as occupying a position for removal; and

Fig. 4 is a section on the line 4—4 of Fig. 2.

Referring to Fig. 3, the matrices are 75 stored in the magazine A and when released therefrom pass into the assembler entrance B, which delivers them to the line assembling mechanism. When the line is composed, it is transported to the casting devices and thereafter carried upward and delivered to the distributing mechanism C, which separates the matrices according to character and returns them through the channel entrance C¹ to the magazine from 85 which they started.

The release of the matrices from the magazine is effected by means of the escapements D, these being of the usual construction and each comprising a rocking lever 90 and a pair of reciprocating pawls which are projected alternately thereby into the magazine at each operation. The escapements are moved in one direction by the springs D¹ and in the opposite direction by 95 the connected vertical reeds D², which are constantly urged and held downward by the stronger springs D³. In the normal position of the parts, the lowermost matrices in the magazine are held against escape by 100 their engagement with the lower pawls of the escapements, which stand projected into the magazine under the influence of the springs D³. When, however, the reeds D² are raised by the key controlled mechanism 105 (not shown), the force of the springs D³ is overcome and the weaker springs D¹ are allowed to act, which then rock the escape-

ments to withdraw the lower pawls to release the lowermost matrices, and simultaneously to project the upper pawls to arrest momentarily the following matrices. Thereafter, the reeds are permitted to descend under the influence of the stronger springs D³, which thus effect the reverse movement of the escapements, withdrawing the upper pawls to allow the matrices which had been 10 momentarily arrested thereby to slide forwardly, and again projecting the lower pawls to arrest the descending matrices and hold them against escape until the next operation. This operation of the escapements is well-known and requires no further description here.

The magazine is supported upon the swinging frame A¹, pivotally mounted at its upper end upon the transverse rod A² (see 20 Fig. 3) and normally resting at its lower end upon the set screws A⁷. The swinging of the frame A¹ is effected by the pair of cams A³ fast to the opposite ends of the transverse rock shaft A⁶ journaled in the 25 frame A¹, the cams being provided with operating arms A⁵ and arranged to coöperate with rollers A⁴ on the main frame. In effecting the removal of the magazine, therefore, it is merely necessary to turn the arms A⁵ 30 forwardly from the position shown in Fig. 1 to that shown in Fig. 3, which action causes the cams to rock the frame A¹ upwardly as illustrated in Fig. 3, when the magazine is free to be drawn forwardly 35 from the machine, the arms A⁵ also giving support to the magazine during such removal. These parts and their mode of operation are also well known and are shown and described in detail in either of the 40 patents to T. S. Homans Nos. 814,542 and 829,868.

In the present instance, the escapements D are attached to or carried by the magazine A, so that before the magazine is rocked 45 upward in the manner just described, the actuating reeds should first be disconnected from the escapements. For this reason, the guide frame D⁴, wherein the reeds are slidably located at their upper ends, is arranged 50 to be moved forwardly and backwardly in the machine in order to connect the reeds with or disconnect them from the escapements. These movements of the frame D⁴ are effected by arms D⁵ connected thereto 55 and fast upon a transverse rock shaft D⁶, which latter is journaled in the framework and provided with an operating handle D⁷.

As before explained, the spring actuated reeds D², when connected to the escapements 60 D, hold them in their normal position against the action of the weaker springs D¹, which tend constantly to rock the escapements in a direction to release the lowermost matrices. It is evident, therefore, that unless means 65 were otherwise provided, the disconnection

of the actuating reeds from the escapements would result in the escape of the lowermost matrices in the magazine, since such disconnection would allow the escapements to be operated by the springs D¹. To prevent 70 this liability, the magazine is provided with a rotary grooved rock shaft E, which when turned to different positions either permits or prevents the operation of the escapements. Fig. 1^a shows the shaft in unlock- 75 ing position, with its groove above the escapement levers, thus permitting their operation, and Fig. 2^a shows it in locking position, with a solid portion in engagement with the escapement levers, thus preventing their operation. It is this latter position the rock shaft should occupy before the actuating devices D² are disconnected from the escapements, and my present invention is directed to means to insure this result. 80

Referring to Fig. 1, the guide frame D⁴ has connected thereto a pivoted latch F having a grip portion F³ and provided on its under side with a locking piece F¹ engaging in front of an upstanding nose or abutment A¹⁰ on the machine frame. Before the frame can be shifted rearwardly, therefore, the latch F must be raised to disengage its locking piece from the abutment A¹⁰. Means are provided to prevent this lifting of the 90 latch until the rock shaft E has been turned to its locking position, such means comprising (see particularly Fig. 4) an arm F² projecting upwardly from the latch F and adapted to coöperate with an enlarged or 95 head portion E² on one end of the rock shaft, which head portion is recessed or reduced as at E³. The relation of these parts is such that when the rock shaft E is in its unlocking position, as in Figs. 1 and 105 1^a, the solid or curved part of the head portion E² stands above the arm F² and thus prevents the lifting of the latch F; and when the shaft is turned to its locking 110 position, as in Figs. 2 and 2^a, the recess E³ is located above the arm F², and thus allows the raising of the latch. In other words, the construction is such that the shifting of the actuating reeds or their disconnection 115 from the escapements cannot be effected until the escapements are first locked against action; or, stated more specifically, the two locking devices for the escapements and the reed shifting-guide, respectively, are so connected or related that the escapement locking device must be moved to active position before the other can be moved to inactive 120 position. In this way, all danger of the matrices "spilling" from the magazine is obviated. 125

In order to hold the rock shaft E positively in either its locking or unlocking position, there is employed a spring detent E^c adapted to engage in one or the other of two recesses E⁵ in the head portion E² of the 130

rock shaft. The detent is slidably arranged in a block A¹¹ secured to the magazine and is provided with an upstanding finger E⁷ to permit its ready disengagement. The rock shaft is also formed with a pair of stop shoulders E⁴, which are adapted to engage on opposite sides of the block A¹¹ to limit the movement of the shaft in opposite directions and to secure the proper registration of the recesses A⁵ with the detent E⁶. The shaft may also be provided if desired with a grip or handle E⁸ to facilitate its turning movements.

Means are also employed to prevent the raising of the magazine for removal until after the escapement reeds have been disconnected from the escapements. These means comprise the hook-shaped arm J connected to the rock shaft D⁶ and adapted to engage a stud A⁹ on one of the cam arms A⁵, when the parts are in their normal position, as shown in Fig. 1. In this position, the cam arm is locked and held against rotation, thus preventing the upward movement of the swinging frame A¹ and the magazine supported thereby. When, however, the handle D⁷ is operated to disconnect the reeds from the escapements, the arm J is moved out of engagement with the stud A⁹, as shown in Fig. 2, and the cam arm may then be manipulated to effect the raising of the magazine, as illustrated in Fig. 3. This specific mechanism is disclosed in my prior Letters Patent No. 1,079,498, but 35 when associated with my present improvements subserves the further function of preventing the removal of the magazine until the escapements have first been locked against action, this result being due to the 40 connection of the arm J with the escapement-reed shifting means, which as before described can only be operated when the escapements have been locked against action.

It is well known that in some machines 45 of the class illustrated, the magazine may be provided with a locking device to engage directly with the contained matrices to hold them therein, instead of engaging with the escapements as shown herein. In both 50 cases, the matrices are locked within the magazine, this result being secured directly in the first case and indirectly in the second. It will be apparent, therefore, that my invention comprehends both arrangements, 55 the essential idea being to insure the locking of the matrices within the magazine before the escapements and their actuating devices are disconnected. However, the use of a locking device to hold the escapements 60 against operation is preferable, possessing certain advantages which would not obtain when it is arranged to coöperate directly with the matrices.

As is also well known, the locking device 65 may be variously modified in form or ap-

plied to many different classes of machines. It is to be understood, therefore, that my invention has been shown merely in preferred form and by way of example and as applied to a particular style of machine, and 70 obviously many modifications and alterations therein and in its mode of application will suggest themselves to those skilled in the art and still be comprised within its scope.

Having thus described my invention, its construction and mode of operation, what I claim and desire to secure by Letters Patent of the United States is as follows:

1. The magazine A provided with the 80 locking rock shaft E formed with the recesses E⁵, and the spring actuated detent E⁶ adapted to engage in one or another of the recesses E⁵, said recesses being located on the rock shaft in such position as to be 85 brought alternately into engaging relation to the said detent as the rock shaft is rotated to active and inactive position respectively.

2. The magazine A provided with the locking rock shaft E formed with the recesses E⁵, and the spring actuated detent E⁶ formed with the upstanding finger E⁷ to facilitate its actuation and adapted to engage in one or the other of the recesses E⁵, the said recesses being located on the rock 95 shaft in such position as to be brought alternately into engaging relation to the detent as the rock shaft is rotated to active and inactive position, respectively.

3. The magazine A provided with the 100 locking rock shaft E formed with the recesses E⁵, and the spring-actuated detent E⁶ adapted to engage in one or the other of the recesses E⁵ so as to hold the rock shaft either 105 in its active or inactive position, the said rock shaft being provided with the stop shoulders E⁴ to limit its rotation in opposite directions and to secure the registration of the recesses E⁵ with the detent E⁶.

4. In a typographical machine, the combination of the magazine A, the escapements therefor, the locking rock shaft E carried by the magazine and formed with the head portion E² having the recess E³, the actuating reeds D² connected to the escapements, 115 and the shiftable guide frame D⁴ provided with the pivoted holding latch F formed with the upstanding arm F² arranged in position to coöperate with the head portion E² of the rock shaft E, in the manner and for 120 the purpose described.

5. In a typographical machine, the combination with the magazine A, the escapements therefor, the locking rock shaft E carried by the magazine and formed with 125 the stop shoulders E⁴ to arrest the shaft in its rotation to active or inactive position and also formed with the head portion E² having the recess E³ facing downward when the shaft is in its active position, the actuat-

ing reeds D² connected to the escapements, and the shiftable guide frame D⁴ provided with the pivoted holding latch F formed with the upstanding arm F² arranged beneath the head portion E², substantially as shown and described.

6. In a typographical machine, the combination of the magazine A, the escapements therefor, the locking rock shaft E carried by 10 the magazine and formed with the recessed head portion E², the swinging supporting frame A¹ whereon the magazine is mounted, the raising cams A³ having the operating arms A⁵, one of the latter being provided with the projecting stud A⁹, the escapement reeds D² connected to the escapements, the shiftable guide frame D⁴ provided with the pivoted holding latch F formed with the upstanding arm F² arranged 15 to coöperate with the head portion E² of the rock shaft E, the rock shaft D⁶ connected to the guide frame D⁴ and provided with the operating handle D⁷, and the locking arm J fast on the shaft D⁶ and 20 adapted to engage the stud A⁹ on the cam arm A⁵, all of said parts coöoperating in the 25 manner and for the purpose described.

7. In a typographical machine, the combination with a magazine, a series of escapements therefor, and actuating members connected to the escapements, of a movable matrix-locking device, a shiftable guide frame for the actuating members, and a movable locking device to hold the guide frame in 30 operative position, the two said locking devices being relatively formed and disposed in such manner that the releasing movement of the frame-locking device is prevented until the matrix-locking device is 35 moved to active position.

8. In a typographical machine, the combination with a magazine, a series of escapements therefor, and actuating members connected to the escapements, of a movable matrix-locking device, a shiftable guide frame for the actuating members, and a movable locking device to hold the guide frame in 40 operative position, the said matrix-locking device acting when in its non-locking position to hold the frame-locking device against 45 movement.

9. In a typographical machine, the combination with a magazine, a series of escapements therefor, and actuating members connected to the escapements, of a movable matrix-locking device, a shiftable guide frame for the actuating members, a movable locking device connected to the guide frame to hold it in operative position, and means intermediate the two locking devices whereby 50 the frame-locking device is held against movement while the matrix-locking device is in inactive position.

10. In a typographical machine, the com-

bination with a magazine, a series of escapements arranged in fixed relation to the magazine, and actuating members connected to the escapements, of a matrix-locking device, a shiftable guide frame for the actuating members, and means controlled by the matrix-locking device for preventing the shifting of said frame until the matrices have been locked in the magazine.

11. In a typographical machine, the combination with a magazine, a series of escapements arranged in fixed relation to the magazine, actuating members connected to the escapements, and means for disconnecting the actuating members from the escapements, of a matrix-locking device movable to active and inactive position, and means controlled by the locking device for preventing the operation of the disconnecting means until said locking device is moved to active position.

12. In a typographical machine, the combination of a removable magazine provided with escapements, actuating members connected to the escapements, a matrix-locking device on the magazine, and means to prevent the removal of the magazine until the matrices have been locked therein and until the actuating members have been disconnected from the escapements.

13. In a typographical machine, the combination of a removable magazine provided with escapements, means for moving the magazine from its operative position to permit its removal, actuating members connected to the escapements, means for disconnecting said actuating members from the escapements, a matrix-locking device on the magazine, and means to prevent the operation of the magazine moving means until the matrices have been locked in the magazine and until the actuating members have been disconnected from the escapements.

14. In a typographical machine, the combination of a removable magazine provided with escapements, escapement-actuating members, a locking device for holding the escapements against operation, and means independent of the escapement-actuating members for preventing the removal of the magazine until the escapements have been locked against action.

15. In a typographical machine, the combination of a magazine provided with escapements, escapement-actuating members, a movable supporting frame whereon the magazine is mounted, a locking device for holding the escapements against operation, and means for preventing the movement of the magazine supporting frame until the escapements have been locked against action.

16. In a typographical machine, the combination of a magazine, a series of escapements arranged in fixed relation to the maga-

zine, actuating members connected to the escapements, a movable locking device to hold the escapements against operation, and means controlled by the locking device for preventing the disconnection of the actuating members from the escapements until the latter have first been locked against operation.

17. In a typographical machine, the combination of a magazine, a series of escapements therefor, actuating members connected to the escapements, a movable locking device to hold the escapements against operation, a shiftable guide frame for the actuating members, a movable locking device to hold the frame in its operative position, and means intermediate the locking devices preventing the movement of the frame-locking device to inactive position until the escape-
ment-locking device is first moved to active 20 position.

18. In a typographical machine, the combination of a magazine, a series of escapements arranged in fixed relation to the magazine, actuating members connected to the escapements, means for disconnecting the actuating members from the escapements, an escapement-locking device movable to active and inactive position, and means preventing the operation of the disconnecting means 25 30 when the escapement-locking device is in inactive position but permitting such operation when said locking device is in its active position.

In testimony whereof, I have affixed my 35 signature.

DAVID S. KENNEDY.
